TYPOGRAPHICAL SLUG CASTING MACHINE

Ransom H. Turner, Great Neck, N. Y., assignor to
 Mergenthaler Linotype Company, a corporation of New York

Application October 31, 1942, Serial No. 464,011

17 Claims. (Cl. 199—47)

1

This invention is directed to an improved complete slug casting machine simple and compact in design and intended to facilitate the production of slugs cast from matrix lines composed in a hand stick.

The machine is equipped with a single slotted mold mounted for quick removal and interchange and carried by a hinged support which is operable during a cycle to swing the mold backwardly and forwardly between the casting and ejecting stations. The mold of less than standard height and the matrices, whose characters range in height from 6 pt. to 72 pt., are formed in their casting edges with routing notches of a depth to compensate for the reduced height of the mold so that slugs cast therein may be of the required "type height." In the preferred embodiment illustrated, the width of the mold slot is 12 pt. and the slugs produced therein from matrix lines of greater point sizes will be of the L-shaped or T-shaped variety, their overhanging type bearing portions being cast in the routing notches of the matrices. The metal pot employed is stationary, being bolted to upright side members of the machine frame, and when the machine is at rest, the mold occupies a position directly in front of the mouthpiece of the pot in casting relation therewith.

Prior to the inauguration of a machine cycle, the hand stick with its composed line of matrices is pushed endwise into a horizontally disposed receptacle and up against a stop which locates the matrix line properly therein with reference to the end walls of the mold slot. The receptacle is slidably mounted in a vertically reciprocable wedge block so that it may be moved relatively thereto downwardly and upwardly to carry the matrix line to and from the casting position; and a screw and dial controlled stop device is employed to arrest the receptacle at different predetermined levels to locate the matrix characters of selected fonts in the proper position transversely of the mold slot. When the cycle is inaugurated, the receptacle is lowered and immediately thereafter the wedge block is pulled downwardly by spring tension to force the receptacle and the mold rearwardly in effecting the necessary "lock-up" preparatory to the descent of the pot plunger. Both the wedge block and mouthpiece of the pot are positively supported during the casting operation by a fixed U-shaped bracket of ample strength, and as a result the casting pressure is increased beyond that which has heretofore been permitted in order to improve the quality of the printing faces of the slugs as well as the slug bodies themselves.

2

The casting mechanism also includes a pressure release valve with control mechanism which may be set in different positions to regulate the extent of the casting period according to the volume of metal displaced by the plunger in casting slugs of different sizes. The valve is mounted in the pump plunger and controlled automatically from the main drive shaft of the machine. In the normal or raised position of the plunger, the valve is partially open in order that the level of the molten metal in the pot crucible and throat may be equalized. During the descent of the plunger, however, the valve is closed and at the end of the predetermined casting period it is opened fully to permit the plunger to partake of its full active stroke before being raised again to its original position.

After the casting of the slug, the wedge block is raised and, in rising, first moves the hand stick receptacle forwardly to forcibly disengage the matrix line from the face of the slug and then (through certain connections later to be described), moves the mold in the same direction a slight distance out of contact with the pot mouthpiece. In its fully raised position, the receptacle stands out of the path of the mold and is readily accessible for the removal and replacement of the hand stick. As the cycle of operation continues, the mold is swung forwardly and downwardly to a horizontal position of rest upon a cross member of the U-shaped bracket (above referred to) where the base of the slug is trimmed and the slug is ejected. The operations of the receptacle, the wedge block, and the mold are all effected in the order and manner stated under the control of a main fore and aft cam shaft arranged directly below the pot.

The slug ejecting mechanism includes as usual a reciprocable ejector slide and an ejector blade detachably connected thereto for interchange at will with blades of different widths. In the present instance, however, the ejector slide operates in a vertical plane and is provided with a subsidiary hinged section which carries the ejector blade. As the slide descends, the blade is first swung over the mold to its active or slug ejecting position and then thrust down through the mold slot to force the slug therefrom and cause it to drop into an underlying trough or galley. After the slug is ejected, the ejector slide rises and the blade section is moved back to its original position out of the path of the mold, which thereupon is swung upwardly and rearwardly to the casting position in front of the mouthpiece of the metal pot as the cycle of operation is completed.

To insure safety in the operation of the ma-

chine, a pump stop and other safety devices are included but these, together with the starting and stopping mechanism, will best be understood from the detailed description to follow.

In the accompanying drawings, the invention has been shown merely in preferred form and by way of example and obviously many changes may be made therein and in its mode of adaptation which will still be comprised within its spirit. It should therefore be understood that the invention is not limited to any specific form or embodiment except insofar as such limitations are specified in the appended claims.

Referring to the drawings—

Fig. 18 is an elevation of a composed line of matrices of different font sizes showing the characters aligned at their bases;

Fig. 19 is a diagrammatic view to indicate the different levels at which matrix lines of selected fonts are supported relatively to the mold; and

Fig. 20 is a vertical section taken on the line 20—20 of Fig. 1.

The matrices X employed in the present machine (Fig. 17) are similar to those used in the machine shown and described in the patents to A. J. Stouges Nos. 1,899,648 and 1,980,110, being generally rectangular in shape and formed with relatively deep routing notches x which extend completely across their casting edges. The matrix

characters x¹ are punched in the bottoms of the routing notches and have a range in size up to 72 pt. in height. Throughout the several fonts, the characters, irrespective of their point size, are positioned for "base alignment" with reference to a common datum line a—b (Fig. 18) when the matrices are composed in line and supported by their bottom edges.

In composing lines of the usual 30 em length, a handstick Y is used, which, as shown in Fig. 15, is rectangular in form and comprises generally the two upper and lower parallel side members Y¹, Y², and the two end walls Y³, Y⁴. The lower side member Y² is provided with a scale y graduated in ems to indicate the length of the matrix lines during composition, and the upper side member Y¹ is provided with an aligning bar Y⁵ which is attached thereto by screw and slot connections y¹ and inclined tongue and groove connections y², so that by moving the bar endwise in opposite directions it will be projected downwardly and upwardly into and out of engagement with the upper edges of the matrices. The handstick Y also includes a pair of abutments or banking blocks Y⁶, Y⁷, arranged respectively adjacent the end walls Y³, Y⁴, and formed in their lower edges with notches y³ to receive a guide rail Y⁸ rising from the lower side member Y² of the hand stick. The abutment Y⁶ is appropriately connected to the free end of a clamping screw Y⁹ mounted in the end wall Y³; whereas the abutment Y⁷ is attached at its upper end to the aligning bar Y⁵, being held in spaced relation with the end wall Y⁴ by an intervening compression spring Y¹⁰ so as to be capable of sufficient lost motion to actuate the bar Y⁵. The matrices X are also formed in their bottom edges with transverse notches x² to receive the guide rail Y⁸ and in their upper edges, they are cut away to fit against the aligning bar Y⁵ which serves to sustain them in proper position on the rail Y⁸ as they are composed in line against the abutment Y⁷. When composition is completed, the matrix line is shifted to the right (Fig. 15) against the influence of the spring Y¹⁰ by the clamping screw Y⁹ and locked thereby in place between the abutments Y⁶ and Y⁷ as the latter banks against the end wall Y⁴, the aligning bar Y⁵ at the same time being cammed downwardly into engagement with the upper edges of the matrices to effect their alignment on the rail Y⁸. The hand stick with its composed line of matrices is now pushed from the right (Fig. 2) into a horizontally disposed channel or receptacle A which fits the upper and lower side walls of the hand stick and which is open at the rear to expose the casting edges of the matrices and closed at the front to give them direct support during the casting period. As best shown in Figs. 2, 6 and 7, the receptacle A is slidably mounted at its opposite ends by tongue and groove connections a¹ in a vertically reciprocable wedge block or clamping member B and is movable therein downwardly and upwardly to carry the matrix line to and from the casting position in front of a slotted mold C. Operation of the receptacle A is effected automatically during a machine cycle, by means presently to be described, and to prevent its operation unless the hand stick is properly positioned therein, said receptacle is locked in its upper or normal position by a vertically disposed latch pawl D (Figs. 1 and 20) which is pivotally mounted at its upper end on a fixed horizontally disposed U-shaped bracket E, and engages beneath a lug or tooth a² projecting

from the contiguous end of the receptacle. The side members E^1 of the bracket E extend forwardly from a metal pot F in the vicinity of the mouthpiece F^1 thereof and embrace the pot casting F^2 to which they are fastened and which in turn is supported upon and rigidly secured to upright side brackets O^1, O^2 of the machine frame. The latch pawl D is limited in its movements by a stop pin d fastened in the bracket E and arranged in a short closed slot d^1 formed in the latch pawl. A pull spring d^2 holds the pawl yieldingly in its active position but when the hand stick is pushed into the receptacle its leading end wall Y^4 is adapted to engage a stud d^3 carried by the pawl and, through such engagement, rock the latter against the influence of the spring d^2 to its inactive position (Fig. 20) to release the receptacle. As the movement of the pawl is arrested by the stop pin d , further movement of the hand stick will also be prevented and it will thus be properly located in the receptacle. Of course, when the hand stick is removed from the receptacle, the spring d^2 will be allowed to restore the pawl D again to its locking position beneath the lug a^2 .

The operating means for the receptacle (Figs. 1, 4, 5, 6 and 7) include a pair of arms A^1 extending forwardly from a rock shaft A^2 and connected by vertical links A^3 with the lower ends of corresponding side members A^4 which are rigidly fastened to the receptacle A . For reasons presently to be pointed out, the side members A^4 are formed at their upper ends with hook-shaped portions A^5 (Fig. 5) arranged to engage corresponding studs c projecting from the opposite ends of the mold C . The rock shaft A^2 is journaled at its opposite ends in the aforementioned side brackets O^1, O^2 of the machine frame and is controlled from a main cam shaft P , being provided with a crank arm A^6 which carries an anti-friction roller a^3 tracking upon a face cam P^1 on the shaft P . A pull spring A^7 , attached to one of the arms A^1 , holds the roller a^3 against the cam P^1 and tends to move the receptacle downwardly; whereas the cam, by rotation of the shaft P , is adapted to act in opposition to the spring to move the receptacle positively in the opposite direction and to sustain it in its uppermost or hand stick receiving position, Figs. 1 and 7.

An angular wiper plate A^8 (Figs. 6 and 7) comprising a horizontal portion A^9 fastened to the top of the receptacle, and a vertical portion A^{10} equipped with a suitable double-faced wiper element A^{11} , is adapted to clean the rear face of the mold as well as the pot mouthpiece F^1 when the receptacle is moved to and from the casting position, the position of the mouthpiece and the mold at the time of the wiper stroke being as shown in Fig. 1. The vertical portion A^{10} of the wiper plate is spaced rearwardly from the receptacle a distance determined by the depth of the mold and is formed with a rectangular opening A^{12} which is sufficiently large to clear the pot mouthpiece at the time of the "lock-up."

To locate the matrix lines composed in the hand stick Y in different casting positions transversely of the mold slot and according to the point size of the font in use, there is provided (see Figs. 4 and 4a) an adjustable stop device G arranged at the right alongside the bracket E and adapted to arrest the receptacle in its downward movement at correspondingly different levels. The stop device G comprises a mi-

crometer screw G^1 and a nut G^2 , which latter is formed with a lateral projection G^3 arranged in a vertical slot e formed in the contiguous side member of the bracket E . The projection G^3 extends through the slot e and, at its inner extremity, is provided with a short track section g disposed in the vertical path of a roller a^4 carried by the receptacle A . The screw G^1 is rotatably mounted in a fixed bearing e^1 and is equipped with a turning knob or handle G^4 for setting the track section of the nut G^2 at different predetermined levels indicated by appropriate markings e^2 arranged adjacent the slot e to be read in conjunction with the upper surface of the projection G^3 . Upon the inauguration of a machine cycle, the receptacle A will be lowered by the pull spring A^7 under control of the cam P^1 until it is stopped in its descent by the banking of the roller a^4 upon the short track section g of the stop device G . After the casting operation and as the cycle continues, the active surface of the cam P^1 (which, due to the arrest of the receptacle, was carried away from the roller a^3) again picks it up and, through the connections before described, raises the receptacle to its original or normal position.

The clamping member or wedge block B (Figs. 4, 5 and 7) includes a horizontal body portion B^1 and a pair of integral end plates B^2 , which latter extend somewhat below the body portion B^1 and contain the aforementioned slots a^1 by means of which the receptacle A is mounted and guided in its vertical movements. The end plates B^2 are also formed with tongues b which are disposed in a plane inclined slightly forward from the vertical and engage in corresponding grooves e^3 formed in the opposed side members E^1 of the fixed U-shaped bracket E . The rear face b^1 of the wedge block fits against the closed vertical front wall of the receptacle A , while the front face b^2 of the block is beveled off at the same angle as that of the tongues b so as to have a sliding fit with a correspondingly beveled surface e^4 formed on the rigid cross member E^2 of the bracket E . The parts are so formed and related that during the downward or active stroke of the wedge block B , the receptacle A (which at such times occupies its casting position in front of the mold C) will be forced rearwardly by the block across the short track section of the stop device G to press the matrix line tightly against the mold; and, conversely, during the return stroke of the block B , the receptacle will be moved forwardly to break contact between the mold and the matrix line, it being understood that such horizontal movements of the receptacle are permitted as a result of the link connections A^3 between the receptacle and its actuating arms A^1 .

The operating means for the wedge block B (Figs. 1, 4, 5, 6 and 7) are similar to those for operating the receptacle A and include, generally, a rock shaft B^3 controlled by a face cam P^2 arranged alongside the cam P^1 on the main shaft P , a pair of arms B^4 extending forwardly from the rock shaft, and a corresponding pair of vertical links B^5 connecting the arms with the end plates B^2 of the wedge block. The rock shaft B^3 is provided with a crank arm B^6 , and the latter is equipped with an anti-friction roller b^3 which tracks upon the cam P^2 . A pull spring B^7 , attached to one of the arms B^4 and anchored to the side frame bracket O^1 , tends to rock the shaft B^3 in a clockwise direction (Fig. 6) and hold the roller b^3 against the cam, so that the active stroke of the wedge block will be impositively effected

by the spring B⁷ while the return stroke thereof will be positively effected by the cam P².

The mold C (Figs. 1, 4 and 6) is detachably fastened to the cross member of a bail-like support C¹ arranged in front of the metal pot F and mounted on a rock shaft C² which is operable during a machine cycle to swing the mold forwardly and backwardly from and to its casting position (Fig. 1). The rock shaft C² is journaled at its opposite ends in small subsidiary brackets E³ fastened to the side members E¹ of the U-shaped bracket E, and is provided with a crank arm C³ which is keyed thereto by a pin and slot connection c¹ so as to permit the mold to be moved independently of the crank arm a slight distance into and out of engagement with the pot mouthpiece F¹ (see Fig. 1).

Operation of the rock shaft C² is effected by a horizontally disposed lever C⁴ connected at its free end by a short vertical link C⁵ with the crank arm C³ and pivoted at its other end in a suitable bearing block o secured to the upright side bracket O¹. The lever C⁴ is controlled from the main shaft P by an edge cam P³ arranged adjacent the cam P² (Fig. 1) and engaging an anti-friction roller c³ mounted at the lower end of an offset arm C⁶ depending from the lever C⁴. A pull spring C⁷, attached to the lever C⁴ and anchored to the side bracket O¹, holds the roller c³ against the cam P³ and tends constantly to turn the rock shaft C² in the appropriate direction to swing the mold C upwardly and rearwardly to the casting position. When the machine is at rest, the roller c³ is engaged with the low concentric portion p of the cam P³ and hence the mold is maintained by the spring C⁷ in its vertical position (Fig. 1) directly in front of the mouthpiece F¹ of the metal pot, in slightly spaced relation therewith. However, during the machine cycle and subsequently to the casting operation, the high portion p¹ of the cam is adapted to engage the roller c³ to raise the lever C⁴ in opposition to the spring C⁷ and, through the rock shaft C, swing the mold forwardly and downwardly to the horizontal ejecting position shown in Fig. 7. After the slug ejecting operation and when the roller c³ is allowed to ride from the high to the low portion of the cam P³, the spring acts to reverse the rotation of the rock shaft and so swings the mold back to its original position.

A brief review of the operation of the parts thus far described may be helpful: As the receptacle A with the composed matrix line is lowered to the casting position in front of the mold C, the wiper element A¹¹ will clean both the pot mouthpiece and the rear face of the mold, and at the same time the hook shaped portions A⁵ of the rigid side members A⁴ of the receptacle will be brought into engagement with the studs c which project from the opposite ends of the mold C. The wedge block B is now lowered in its inclined guideways e³ under the influence of the pull spring B⁷ and acts to force the receptacle as well as the mold rearwardly in effecting the "lock-up" of the parts, that is to say, with the mold clamped firmly against the mouthpiece of the pot and the matrix line clamped firmly against the front face of the mold. After the casting of the slug, the wedge block B is moved upwardly against the action of the spring B⁷, as before described, and in rising pulls the receptacle forwardly so as, first, to disengage the matrix line from the face of the newly cast slug and, then, through the hook-shaped portions A⁵,

forcibly restore the mold to its former position in spaced relation with the pot mouthpiece F¹. Subsequently, the receptacle is restored to its uppermost or normal position and the mold is then swung forwardly and downwardly to its horizontal position (Fig. 7) where the slug is ejected. During the upward movement of the receptacle, the mold and the pot mouthpiece are again subjected to the action of the wiper element A¹¹.

As well known, in casting slugs from the larger or headletter matrices, say, between the 36 pt. and 72 pt. range, much greater pressure and speed in the drop of the pump plunger are required than when casting from matrices of the lower point sizes, in order to approach the degree of perfection desired in the quality of the slug printing faces as well as in the solidity of the slug bodies. Heretofore, springs of a limited strength have been depended upon to maintain the necessary "lock-up" and, as a result, the casting pressure has been limited accordingly. As a feature of the present invention, a positive instead of an impositive "lock-up" is contemplated, and to this end, the mouthpiece F¹ of the metal pot (see Fig. 2) is supported independently of the pot by lugs E⁴ which project inwardly from the side members E¹ of the bracket E to engage behind corresponding lugs F³ formed at the opposite sides of the pot throat adjacent the mouthpiece. Consequently, the pressure created by the casting operation will be absorbed entirely by the bracket E between the lugs E⁴ at the rear and the cross member E² at the front, and may therefore be as great as the tensile strength of said bracket will permit.

The mold C is supported at the ejecting station (Figs. 6, 7 and 8) by a rigid cross bar E⁵ of the bracket E, said bar being disposed below the cross member E² thereof and formed with a depression or recess E⁶ wherein the mold is located in a horizontal position with its rear face flush with the upper surface of the cross bar E⁵ (see Fig. 7). Just prior to the ejecting operation, the base of a slug cast in the mold is trimmed by a knife H which is secured to a horizontally reciprocable slide H¹ and adapted to be moved thereby to and fro across the mold. The knife slide H¹ (Figs. 3-6 and 8) is mounted by tongue and groove connections h in the side members E¹ of the bracket E and is operable from a rock shaft H² through a pair of spaced-apart vertical arms H³ connected at their upper ends by intermediate links H⁴ with the opposite ends of the slide. The rock shaft is mounted between forward extensions O³ of the upright frame bracket O¹, O² and is controlled from a face cam P⁴ which is located on the shaft P in front of the mold cam P³ and engages a roller h¹ carried by a crank arm H⁵ depending from the rock shaft. The cam P⁴ imparts the active or cutting stroke to the knife slide H¹, while a pull spring H⁶, connected with one of the arms H³ of the rock shaft and acting in opposition to the cam, imparts the return stroke thereto, although under control of the cam.

After the slug has been trimmed, it is ejected from the mold C by the operation of an overhead vertically reciprocable ejector slide J which, like the knife slide H¹, is mounted and guided by means of tongue and groove connections j in the opposing side members E¹ of the bracket E. The slide J is equipped as usual with a detachable ejector blade J¹ but, in the present instance, the

blade (as shown in Figs. 6 and 8) is attached to a plate J^2 suspended from a hinge pin J^3 mounted on the slide, so that it may be swung forwardly from its active position (Fig. 7) in line with the slide to its inactive position (Fig. 6) out of the path of the mold. Such movement of the ejector blade are effected automatically during the reciprocation of the ejector slide and are controlled by an angular cam slot e^5 formed in the contiguous side member of the bracket E and arranged to receive a stud j^1 projecting laterally from one end of the plate J^2 . When the ejector slide J starts its descent, the plate J^2 will be cammed rearwardly by the inclined portion of the slot e^5 to locate the blade in a position directly over and in line with a slug cast in the mold C ; and after the slug is ejected from the mold and the slide nears the completion of its return stroke, the plate J^2 will be cammed forwardly to its original position by the same inclined portion of the slot e^5 . The vertical portion of the slot e^5 acts to maintain and guide the ejector blade during the actual slug ejecting operation. Slugs ejected from the mold C pass downwardly through an aperture E^7 formed in the cross bar E^5 below the depression E^6 and are deposited in an underlying inclined trough or galley E^8 supported from the bracket E and arranged for convenient accessibility at the front of the machine. To prevent possible damage to the printing faces of the slugs as they drop to the galley E^8 , they are subjected to the influence of a flexible deflector element E^9 fastened to the bottom of the crossbar E^5 and adapted to turn the slugs and cause them to assume the positions indicated in dotted lines (Fig. 7) as they slide down the galley.

The ejector slide J is operated from a rock shaft J^4 (Figs. 6 and 8) arranged alongside the rock shaft H^2 and provided with a pair of arms J^5 , J^6 extending forwardly therefrom and connected by a corresponding pair of vertical links J^7 with individual bracket plates J^8 secured to the opposite sides of the ejector slide. The rock shaft J^4 (Fig. 1) is mounted at its opposite ends in the forward extensions O^3 of the upright frame brackets O^1 , O^2 and is controlled from the main shaft P by a face cam P^5 arranged in front of the knife operating cam P^4 and engaging an anti-friction roller j^2 carried by a crank arm J^9 depending from the rock shaft. The cam P^5 presents a high portion p^2 and a low portion p^3 ; and immediately following the operation of the knife slide H^1 , the high portion p^2 is adapted to engage the roller j^2 and turn the rock shaft J^4 in the appropriate direction to impart the active or downward stroke to the ejector slide through the arms J^5 , J^6 and the links J^7 . This operation takes place in opposition to the pull spring H^6 for the knife slide, which spring (as shown in Fig. 1) is connected to a lug j^3 rising from the arm J^5 and serves to reverse the rotation of the rock shaft J^4 as the high portion of the cam P^5 passes the roller j^2 in order to impart the return stroke to the ejector slide. As soon as the slide attains its uppermost position with the ejector blade out of the path of the mold C , the latter is restored to the casting position in front of the mouthpiece of the metal pot F in the manner before described, and the cycle of operation is completed.

Reference is now directed to Figs. 1, 9, 10 and 11 which illustrate the mechanism controlling the operation of the pump plunger during the casting period. The plunger F^4 (Fig. 1) is mounted as usual to reciprocate in a well F^5 of the pot crucible

F and is operated by an overhead lever F^6 which is secured to one end of a short fore and aft rock shaft F^7 and connected with the plunger by an intermediate link F^8 . The rock shaft F^7 is mounted in an offset bearing member of the pot casing F^2 and at its rear end it is provided with a crank arm F^9 connected with one arm of a bellcrank lever F^{10} pivoted to the pot supporting bracket O^2 . The other arm of the lever F^{10} is equipped with an anti-friction roller f which tracks upon a spiral-shaped edge cam P^6 arranged behind the bracket O^2 and keyed to the main shaft P . When the machine is at rest, the roller f is engaged with the highest concentric portion p^4 of the cam P^6 and the pump plunger, through the connections just described, will be sustained by the cam in its raised position against the influence of a powerful vertically disposed pull spring F^{11} which is attached at the top to the overhead lever F^6 and anchored at the bottom to the base portion of the bracket O^2 . However, at the proper moment during a machine cycle, the roller f is adapted to ride off the high portion of the cam P^6 and permit the spring to actuate the lever F^6 and cause the descent of the pump plunger. Molten metal from the pot well will thus be forced upwardly through the mouthpiece of the pot into the mold C and against the composed line matrices in the hand stick Y . As the cycle proceeds and the plunger is allowed to complete its descent, the roller f will engage the gradual rising low portion p^5 of the cam, so that the plunger will be slowly raised and finally restored to its original position of rest. In this connection, it may be stated that, due to the comparatively short space of time required in effecting the "lock-up" after the inauguration of the machine cycle, approximately 200° in the rotation of the cam P^6 may be devoted to raising the plunger and extending the spring F^9 ; consequently, the spring may be of maximum strength without overburdening the main driving clutch and thus create a correspondingly high pressure at the time of casting, it being understood that the force under which the metal is projected into the mold is one of the determining factors in the quality of slug printing faces, particularly when matrices of the larger and bolder fonts are employed.

The control mechanism for the pump plunger F^4 includes also a so-called "quick-drop" device to further augment the casting pressure; and, as shown in Figs. 9 and 10, this device comprises merely a depending finger f^1 fastened to the lever F^{10} at a point adjacent the roller f and adapted by rotation of the cam P^6 to engage a hardened wear plate p^6 carried by the cam and projecting slightly beyond the high portion p^4 thereof so as to sustain the lever F^{10} momentarily and independently of the roller, and then permit it to drop suddenly to bring about the casting operation.

Another important factor to be considered in determining the quality of the slug printing faces as well as the solidity of the slug bodies is the length of time the casting pressure is maintained, it being also understood that, to accomplish the best results, a longer period of time should be allowed for the "freezing" or solidification of the larger heavier slugs in the mold and routing notches of the matrices than for those of smaller size. To this end, therefore, the pump plunger F^4 (Figs. 1 and 11) is equipped with a pressure release valve K controlled from the main shaft P by an actuator K^1 , which latter is ad-

justably mounted on the hub portion of the cam P^6 so that it may be set in different angular positions to time the operation of the valve according to the volume of metal to be displaced by the plunger in casting slugs of a given size. The valve K (Fig. 11) is slidably mounted for vertical movement in the plunger F^4 and is grooved longitudinally to serve as a by-pass for the molten metal from the pot crucible into the pot well during the rise of the plunger to its uppermost position. Operation of the valve K (Figs. 9 and 10) is effected from an upright lever K^2 through the medium of a rock shaft K^3 and a vertical link K^4 which connects the valve with an arm K^5 projecting from one end of the shaft over the metal pot F . The rock shaft K^3 (Figs. 2 and 9) is rotatably mounted in a hole drilled longitudinally and concentrically through the shaft F^4 , and at its rear end, it is provided with a depending crank arm K^6 arranged alongside the arm F^9 and equipped at its lower extremity with an anti-friction roller k disposed in engaging relation with the upper end of the upright lever K^2 . A pull spring K^7 , attached at one end to the crank arm K^6 and at its opposite end to the arm F^9 , holds the former resiliently against a fixed stop pin k^1 with the pressure release valve partially open so as to insure equalization in the level of the metal in the pot throat and crucible through communicating ports F^{12} and F^{13} formed respectively in the pump plunger F^4 and the pot well F^5 (Fig. 11).

The upright lever K^2 is mounted at its lower end on a fixed hinge pin k^2 and provided with an anti-friction roller k^3 disposed in the path of a beveled cam surface k^4 formed on an arm K^8 of the actuator K^1 . A detent K^9 , carried by the arm K^8 and engaging a notched sector plate K^{10} , locks the actuator in its adjusted positions against rotary movement relatively to the cam shaft P . During rotation of the shaft P in the direction indicated (Fig. 10) and, as the cam surface k^4 engages the roller k^3 , the lever K^2 will be swung to the left against the roller k of the crank arm K^6 and thus turn the rock shaft K^3 in the appropriate direction to open the valve K . As the arm K^8 passes the roller k^3 , a pull spring K^{11} , attached to the lever K^2 and urging it in the opposite direction, is allowed to restore it to its original position against a fixed stop pin k^5 . The sector plate K^{10} (Fig. 10a) is fastened to a collar P^7 keyed to the shaft P , and adjacent the notches therein, it is provided with markings k^6 which facilitate the adjustments of the actuator and indicate the point size of the matrix font in use. By disengaging the detent from the sector plate, the actuator may be turned and reset in different selected positions to vary the distance between the cam surface k^4 and the roller k^3 and thus change the timing in the operation of the upright lever K^2 and the pressure release valve K .

It will now be seen (Figs. 9, 10 and 11) that, as the finger f^1 of the lever F^{10} during a machine cycle, rides off the wear plate p^6 of the cam P^6 , and the plunger F^4 starts its descent, the valve K will be closed immediately so as to shut off communication between the metal in the well and that in the crucible and cause the plunger to be arrested in its descent at one level or another according to the volume of metal it displaces in filling the mold and routing notches of the matrices, reasonable allowance being made for the slight space existing in the pot throat in the vicinity of the mouthpiece F^1 . As the cycle proceeds and the lever K^2 is actuated to re-open

the valve K in the manner above stated, the plunger is allowed to continue its descent until the roller f of the lever F^{10} engages the cam P^6 . During the rise of the plunger, the valve K will remain open for the reasons before stated, since the strength of the pull spring K^7 will be insufficient to overcome the resistance of the metal above the valve until the plunger attains its uppermost position. The period of time allowed to elapse between the drop of the plunger F^4 and the reopening of the valve K will of course be determined by the adjusted position of the actuator and will be longer when casting the larger slugs and shorter when casting the smaller slugs.

15 The casting mechanism, as in most machines of the class described, is equipped with a so-called "pump stop" attachment adapted to prevent the descent of the pump plunger F^4 and the resultant danger of a metal squirt in the event that the 20 "lock-up" should not be properly effected. This attachment (see Figs. 4 and 5) includes a bifurcated or U-shaped stop slide Q mounted for a limited fore and aft movement in fixed guideways q upon the pot casing and arranged directly below the overhead plunger actuating lever F^6 . The side members q^1, q^2 of the slide Q are disposed in engaging relation with the lower edges of corresponding banking plates q^3, q^4 secured respectively to the opposite sides of the lever F^6 , and, as the 25 slide is moved to and fro, the stop members will be positioned alternately beneath the banking plates. Operation of the slide Q , in the present instance, is controlled from the wedge block B through a bellcrank lever Q^1 and an intermediate 30 fore and aft link Q^2 , the latter being attached at its rear end to a forward extension q^5 of the slide Q and at its front end to one arm of the lever Q^1 . A pull spring Q^3 , connected with the lever Q^1 and anchored to the bracket E , holds the lever 35 resiliently against a stop pin q^6 with the slide Q located in its normal position (indicated by the dotted lines in Fig. 5) and the stop member q^1 thereof positioned directly beneath the banking plate q^3 of the plunger actuating lever F^6 . The other arm of the bellcrank lever Q^1 is formed with an offset portion q^7 disposed in the vertical path of a set screw b^5 carried by the wedge block B and mounted in a lug b^6 projecting laterally from the contiguous end plate B^2 thereof. As the wedge 40 block approaches the limit of its downward movement in effecting the "lock-up," the set screw b^5 is adapted to engage the offset portion of the lever Q^1 and shift the slide Q to the inactive position shown by the full lines in Fig. 5 so as to displace the stop member q^1 from beneath the lever F^6 and thus permit the drop of the pump plunger to take place in the manner already described. However, if the wedge block should happen to be arrested in its descent, the slide Q would remain in 45 its original position and the operation of the plunger would be prevented by the banking of the plate q^3 of the plunger lever upon the stop member q^1 of the slide. Moreover, if the wedge block should be allowed to descend beyond the limit of 50 its active stroke (as would be the case if the mold were not in the casting position at the time or if the receptacle A for any reason should fail to descend after being released by the latch pawl D), the stop slide Q would then be shifted slightly 55 further forwardly by the lever Q^1 a distance determined by a pin and slot connection q^8 and thus position the other member q^2 of the slide beneath the banking plate q^4 of the lever F^6 and so lock the pump plunger against operation.

70 The driving mechanism and control devices of

the improved machine will now be described, reference being made to Figs. 12, 13 and 14. The cam shaft P is mounted at its opposite ends in stationary bearing brackets O⁴, O⁵ of the machine frame and receives its motion from a hollow fore and aft drive shaft L through the medium of a friction clutch M and a train of reducing gears including, generally, a large gear L¹ mounted to rotate on a fixed stub shaft L² and meshing with a driving pinion L³, a small gear L⁴ also mounted on the stub shaft and preferably formed integrally with the gear L¹, and a gear L⁵ keyed to the cam shaft P and meshing with the small gear L⁴. The clutch M (Fig. 12) comprises two opposing members M¹, M², the former secured to a motor driven wheel M³ mounted to rotate on the drive shaft L, and the latter splined to the rear end of said shaft and attached to a push rod M⁴ which is mounted in the drive shaft and movable endwise therein to carry the member M² into and out of engagement with the member M¹. The engagement of the clutch members is effected by a compression spring M⁵ seated in the shaft L behind a collar m¹, and the disengagement thereof is effected by a lever L⁶ controlled from the main shaft P and having its right arm engaged with the push rod M⁴ in front of the collar m¹. The lever L⁶ is mounted to turn about a fixed vertical axis l and has its left arm equipped with a slide bar L⁷ projecting slightly beyond the end of the arm into the path of a finger L⁸ of a cam plate L⁹ which is carried by a disc L¹⁰ fastened to the shaft P. The finger L⁸ (Fig. 14) is formed with a bevel or cam surface l¹ and, just before the shaft P completes a revolution in the direction indicated (Fig. 13), this cam surface l¹ is adapted to engage a corresponding cam surface l² formed on the slide bar, so as to rock the lever L⁶ in the proper direction to disengage the clutch M. Overthrow of the cam shaft at this time is prevented by a lip l³ projecting laterally from the finger L⁸ above the cam surface l¹ and adapted to bank upon the projecting portion of the slide bar L⁷ as soon as the clutch is disengaged.

As shown in Fig. 13, the cam plate L⁹ is rotatably mounted on the shaft P and attached to the disc L¹⁰ by means of a screw and slot connection l⁴ which permits the cam plate (for reasons about to appear) to be turned a limited distance relatively to the disc against the influence of a light pull spring P when the two cam surfaces l¹ and l² are brought together. The slide bar L⁷ is operable by a bell crank lever L¹¹ arranged just above the lever L⁶ and connected by a long fore and aft link L¹² with a hand lever L¹³ located conveniently at the front of the machine. When the hand lever is pulled forwardly (Fig. 12), the bellcrank lever will be rocked in the appropriate direction in opposition to a spring l⁶ to withdraw the slide far enough from its position beneath the lip l³ to permit the spring l⁶ to snap the cam plate down out of the way of the contiguous end of the bar before the hand lever is released. By the same action, the lever L⁶ is released and the clutch spring M⁵ allowed to engage the clutch M to start the operation of the machine. When the machine cycle is nearly completed, the cam plate L⁹ through its engagement with the slide bar L⁷ will first be turned upwardly the limited distance permitted by the screw and slot connection l⁴ against the feeble resistance of the weak spring l⁶ and then actuate the lever L⁶ as above described to disengage the clutch and stop the operation of the machine.

Provision is also made for stopping the oper-

ation of the machine at will at any time during cycle, and to this end, the hand lever L¹³ (Fig. 12) is operatively connected by a toggle L¹⁴ with a fore and aft slide rod L¹⁵ mounted in fixed spaced apart bearings o³, o⁴ and arranged with its rear end directly opposed to the front end of the push rod M⁴. When the hand lever is pushed rearwardly, the toggle will be straightened out and both rods will be forced in the same direction to overcome the pressure of the spring M⁵ and disengage the clutch M. Conversely, when the toggle is collapsed by reversing the operation of the hand lever, the spring M⁵ will again act to re-engage the clutch to complete the machine cycle of operation. Sufficient lost motion is allowed at the point of connection between the link L¹² and the hand lever, as shown in Fig. 12, to permit its operation at such times without disturbing the bellcrank lever L¹¹ and the slide bar L⁸.

From the foregoing description, the construction and operation of the parts should be clear without further elaboration. However, it may be stated that, in addition to the features hereinbefore described in detail, the machine is simple in design and cheap to manufacture, with no heavy levers or springs of extraordinary strength except those for actuating the pump plunger. The load on the driving mechanism may therefore be reduced to a minimum and the size of the cams as well as the capacity of the motor employed may be reduced accordingly.

Having thus described my invention, what I claim is:

35. 1. In a slug casting machine, the combination of a mold, a line receptacle or holder mounted for movement into and out of contact with the mold, and a reciprocable wedge block mounted in fixed guideways and connected with the receptacle for clamping the matrix line against the mold preparatory to the casting operation.
40. 2. A combination according to claim 1, including a stationary metal pot to cooperate with the mold and wherein the fixed guideways for the wedge block are mounted in an integral bracket member attached to the metal pot.
45. 3. A combination according to claim 1, including a main drive shaft for the machine, and wherein the receptacle is movably mounted in the wedge block to carry the line into and out of cooperative relation to the mold, and including separate and distinct means controlled from the main drive shaft of the machine for operating the wedge block and the receptacle, respectively.
50. 4. In a slug casting machine, the combination of a stationary metal pot, a mold movable bodily into and out of contact with the mouthpiece of the pot, a line receptacle or holder movable bodily to carry the line into and out of contact with the mold, and a reciprocable wedge block mounted to slide in fixed guideways and controlling such movements of both the mold and the receptacle.
55. 5. A combination according to claim 4, wherein the receptacle is connected directly with the wedge block and the movements of the mold are effected through the medium of the receptacle.
60. 6. A combination according to claim 4 wherein the receptacle is connected directly with the wedge block and including connections between the receptacle and mold whereby the movements of both are effected positively by operation of the wedge block.
65. 7. In a slug casting machine, the combination of a stationary metal pot, a vertically disposed

mold normally arranged in closely spaced cooperative relation to the mouthpiece of the pot and mounted for horizontal movement into and out of contact with the pot, a line receptacle or holder normally arranged above the level of the mold and movable downwardly to position the line in closely spaced cooperative relation to the mold, said receptacle or holder being mounted for horizontal movement when occupying its downward position into and out of contact with the mold and automatic clamping means operative after such downward movement of the line receptacle to press the mold into firm contact with the pot mouthpiece and the line into firm contact with the mold in effecting the proper "lock-up" of the parts preparatory to the casting operation.

8. A combination according to claim 7, wherein in the line receptacle after casting is raised back to its original position and wherein the mold is pivotally mounted so as then to be swung facewise downwardly to a horizontal position for the slug ejecting operation.

9. A combination according to claim 7, wherein in the line receptacle after casting is raised back to its original position and the mold then swung facewise downwardly to a horizontal position for the slug ejecting operation, and including a vertically disposed ejector slide movable downwardly when the mold reaches its horizontal position to drive the slug from the mold.

10. A combination according to claim 7, wherein in the line receptacle after casting is raised back to its original position and the mold then swung facewise downwardly to a horizontal position for the slug ejecting operation, and including a horizontally reciprocable knife movable across the rear face of the mold to trim the base of the contained slug when the mold reaches its horizontal position.

11. A slug casting machine including, in combination, a stationary metal pot having a horizontally disposed mouthpiece, a mold mounted for horizontal movement into and out of contact with the mouthpiece of the pot, a matrix line receptacle or holder mounted for vertical movement to and from the casting level as well as for horizontal movement into and out of contact with the mold, and automatic clamping means for effecting a positive "lock-up" between the matrix line, mold and pot mouthpiece preparatory to the casting operation.

12. A machine according to claim 11 including adjustable means for arresting the matrix line receptacle or holder in its downward movement at the required casting level.

13. A machine according to claim 11, including a stop member disposed in the downward path of movement of the matrix line receptacle or holder and capable of adjustment to vary the

casting level thereof so as to locate the matrix characters of different fonts in proper casting position transversely of the mold cavity.

14. A combination according to claim 4, including safety means to prevent the casting operation in the event of interference in the normal operation of the wedge block.

15. In a slug casting machine equipped with a stationary metal pot having a horizontally disposed mouthpiece and with a vertically disposed ejector located in spaced relation thereto at the front thereof, the combination of a mold, a hinged support therefor to sustain the mold in a vertical plane for cooperation with the mouthpiece of the metal pot during casting, and movable to locate the mold in a horizontal plane for cooperation with the slug ejector after casting, and automatic means for operating the mold support.

16. In a slug casting machine equipped with a slug ejecting mechanism, the combination of a mold, a hinged support therefor adapted to sustain the mold in a vertical plane at the casting station, automatic means for operating the support so as to swing the mold facewise to and from a horizontal plane at the ejecting station, a fixed recessed bar for locating and sustaining the mold independently of its support during the slug ejecting operation, and a trough or galley underlying the bar to receive a slug ejected from the mold.

17. In a slug casting machine equipped with a slug ejecting mechanism, the combination of a mold, a hinged support therefor adapted to sustain the mold in a vertical plane at the casting station, and automatic means for operating the support so as to swing the mold facewise to and from a horizontal plane at the ejecting station, characterized by the fact that the slug ejecting mechanism includes a vertically reciprocable ejector slide located over the mold ejecting station, and an ejector blade connected with the slide and movable relatively thereto into and out of active position during the operation of the slide.

RANSOM H. TURNER.
